Atlys.

UNITED STATES PATENT OFFICE.

GEORGE H. RAUSCH, OF EAST BOOTHBAY, MAINE.

MATERIAL FORMED FROM FISH-SKINS AND METHOD OF PREPARING THE SAME.

1,372,192.

Specification of Letters Patent. Patented Mar. 22, 1921.

Application filed April 30, 1920. Serial No. 378,028.

To all whom it may concern:

Be it known that I, GEORGE H. RAUSCH, a citizen of the United States, and a resident of East Boothbay, in the county of Lincoln and State of Maine, have invented an Improvement in Materials Formed from Fish-Skins and Methods of Preparing the Same, of which the following description, in connection with the accompanying drawings, is a specification, like characters on the drawings representing like parts.

This application is a continuation in part of my application Serial No. 247,456, filed July 30, 1918.

15 This invention relates to a novel prepared material of the nature of leather and to a process of preparing the same.

As an aid to comprehension of my invention I have herein disclosed the same in connection with a particular use thereof in the formation of a shoe sole for which it offers peculiar advantages. I do not, however, claim in the present application the construction of the shoe in itself and do not wish to be understood as limiting the scope of my invention, as claimed herein, to such a use.

My invention will best be understood by reference to the following description taken in connection with the annexed drawing 30 wherein:

Figure 1 is a bottom view of a shoe with the thicknesses of the sole turned back;

Fig. 2 is a view of the material which I use, as a prepared section thereof would be seen through the microscope, the figure being very much enlarged over natural size, say between one hundred and fifty and two hundred times; and

Fig. 3 is a plan view of the material and corresponds to Fig. 2.

As an example of the application of my invention I here show a shoe having a sole one of the intermediate thicknesses of which, as for example the thickness 5, shown in Fig. 1 as interposed between the insole 7 and the outer sole 9, is composed of a layer of dogfish skin cured, as for example by tanning, and preferably further prepared as herein described in order to make it particularly available for use in foot gear.

The layer 5 consists of the whole skin of the common dogfish of the New England coast, which is also known as grayfish and of which I believe the scientific name to be

55 *Squalus acanthias.*

A characteristic feature of this skin is the presence of what I shall call teeth 11, these being, as I understand, placoid scales. These elements 11, as shown on a greatly enlarged scale in section in Fig. 2, consist of a basal 60 plate of dentin of dermal origin embedded in the skin and bearing a projecting portion or spine covered with enamel. When a section of the skin prepared for the microscope is viewed with the naked eye, these teeth 65 have somewhat the appearance of the wires of card clothing although on a much smaller scale. The bases of the teeth appear to be arranged in staggered relation, as indicated in Fig. 3, and as shown in Fig. 2 they overlap serially more or less, providing an almost continuous covering for the skin.

The presence of the teeth referred to has hitherto been thought an insuperable difficulty in utilizing the skin as they catch and prevent the material from being handled conveniently or from being spread out in contact with other materials. As they are very securely attached to the skin proper, efforts to remove them have hitherto not 75 been successful as such efforts involved damage to the skin itself. At the same time, the presence of these spines contributes to the wearing quality of the skin and also to the waterproof quality. The latter is so 80 marked that it has been asserted that dogfish skin leather does not "breathe."

Referring further to Fig. 2, the main portion of the skin appears to embody layers of fibers 13 and 15, the direction of the fibers 90 in adjacent layers being crossed, occasional fibers passing from one layer to another in the manner of warp threads and binding the layers together. This structure provides a very strong and unyielding skin.

In accordance with my invention I cure the skin in any suitable manner, as by tanning. During the curing operation I avoid as far as possible mechanical strain of the skin and strive for a gentle curing operation 100 which will preserve as far as possible the material of the skin to give a firm and strong product. Thereafter I treat it with a suitable material, preferably of a waterproofing nature, either by impregnating or 105 impregnating and thereafter coating the skin therewith in such a manner as to provide a thickness of material which will fill in the spaces between the teeth. This waterproofing also serves to fill up any interstices in 110

the skin itself which may have been opened between the fibers by the curing process, thus reintegrating its quality of resistance to water.

- 5 Various materials which may be applied in this manner will suggest themselves to those skilled in the art. As examples I may mention a mixture of paraffin and rosin dissolved, a mixture of paraffin and rubber or other suitable gums, and linseed oil and rubber. If the prepared skin is to be used as herein disclosed in a shoe, the material should be so chosen as to form at least temporarily a proper adhesive joint with the cements which are ordinarily used in shoe manufacture for temporarily holding parts together and which usually have a basis of rubber. The materials specified answer this requirement.
- 10 After the skin has been treated in this manner, I smooth the toothed surface, conveniently by buffing or scraping the same or by a calendering operation. In Fig. 2 I have shown the coating of waterproofing material 17 filling the spaces between the teeth and the smoothing operation may extend to the line $a-a$, thus partially removing the teeth 11, as for example by breaking or blunting their points or bending them down. The presence of the waterproofing layer acts to position the teeth and permits this smoothing or breaking of them without any tendency to break them loose from their places in the skin itself so as to mar the same.
- 15 I am thus enabled to prepare a material having a smooth surface and which is therefore convenient to handle and at the same time to preserve with comparatively little change the dentin covering of the skin which adds to its wear-resisting qualities and to its waterproof character.
- 20 The skin prepared in this way is very thin as compared with ordinary animal leathers and at the same time exceedingly tough and elastic. Its natural water-resisting qualities are very great and these are reinforced by the coating material 17 which also masks the sharp teeth and permits the material to be handled, thus, for example, to be conveniently assembled in a shoe sole with other parts of the sole. At the same time, the resisting qualities of the skin due to the presence of the teeth are preserved and the skin proper as distinguished from the teeth is in no way damaged by any attempt to remove the teeth. From one aspect it might be said that I provide a means masking the teeth and forming as it were a vehicle whereby the natural dentin layer may be conveniently applied to use and will be protected during use so that its resistant qualities may be fully utilized. Obviously the coating may vary in accordance with the purposes to which the skin is to be applied,

the flexible plastics specified being well adapted for use when the skin is to be made part of a shoe. Both because of its natural strength and because of its preventing the passage or soaking of water from one thickness of the sole to another, as from 9 to 7 or vice versa, the skin serves to hold a shoe in shape and prevents the wear in shoes due to an unevenness or sagging of the sole. At the same time, the wearer is well protected against dampness.

75 Beside the particular advantages of dogfish skin as described herein, the material is cheap and it is most desirable to utilize these fish in some manner in order to somewhat reduce the numbers thereof, since they prey upon food fishes.

Having thus described my invention, what I claim as new and desire to secure by Letters Patent is:—

1. As a new article of manufacture, cured dogfish skin having a water-resisting coating applied thereto filling the spaces between the teeth thereof and providing a substantially smooth surface therefor.

2. As a new article of manufacture, skin as described in claim 1 wherein the waterproofing material is of a nature to adhere to cement.

3. As a new article of manufacture, cured dogfish skin having the spaces between the teeth thereof filled with a coating of material adapted to adhere to cement and providing a substantially smooth surface therefor.

4. As a new article of manufacture, a cured fish skin having placoid scales or teeth and having a water-resisting filling in the spaces between the teeth, providing a substantially smooth surface for the skin.

5. As a new article of manufacture, a cured fish skin having placoid scales or teeth and having a coating applied to the toothed side thereof filling the spaces between the teeth, the ends of the teeth being presented at the outer side of the coating and the whole being smoothed.

6. That process of preparing dogfish skin comprising treating the cured skin to fill the spaces between the teeth thereof and smoothing the toothed surface so prepared.

7. That process of preparing fish skins of the type having placoid scales, comprising treating the cured skin with a waterproofing material filling the spaces between the teeth and smoothing off the toothed surface.

8. That process of preparing dogfish skin comprising coating the toothed surface thereof with a flexible plastic and thereafter smoothing the surface and the tips of the teeth.

In testimony whereof, I have signed my name to this specification.

GEORGE H. RAUSCH.
